Primary Examiner — Marissa J. Cash*Assistant Examiner* — Kayla Marie Bennett(74) *Attorney, Agent, or Firm* — Bartholomew Law PC; Michael Bartholomew(57) **CLAIM**

The ornamental design for a hole positioner as shown and described.

DESCRIPTION

FIG. 1 is a front, left and top perspective view of a hole positioner, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The dash-dash broken lines shown in FIGS. 1-9 illustrate portions of the hole positioner that form no part of the claimed design; The dot-dash broken lines shown in FIGS. 1 and 9 are for purposes of annotating the enlarged view only and form no part thereof.

1 Claim, 9 Drawing Sheets(56)
